CLAIM

The ornamental design for a case for electronic communications device, as shown and described.

DESCRIPTION

FIG. 1 is a front perspective view of a case for electronic communications device showing my new design; FIG. 2 is a rear perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a front perspective view showing the inner shell component of the case in isolation; FIG. 10 is a rear perspective view showing the inner shell component of the case in isolation; FIG. 11 is a front perspective view showing the outer frame component of the case in isolation; FIG. 12 is a rear perspective view showing the outer frame component of the case in isolation;

FIG. 13 is an exploded front perspective view showing the components of the case separated for clarity of disclosure; FIG. 14 is an exploded rear perspective view showing the components of the case separated for clarity of disclosure; FIG. 15 is an enlarged detail view of the encircled region of FIG. 2;

FIG. 16 is an enlarged detail view of the encircled region of FIG. 4; and,

FIG. 17 is a cross-sectional view of the case for electronic communications device taken along the line 17-17 of FIG. 4.

Although the case for electronic communications device in which the claimed design is embodied comprises an inner shell and an outer frame, the claim is directed to the ornamental appearance of the case in its entirety and does not extend to the ornamental appearance of each of the individual components of the case in isolation.

The dash-dot broken line circle in FIGS. 2 and 4 delineates a portion of the case for electronic communications device that is part of the claimed design and that is shown on an enlarged scale in FIG. 15 and FIG. 16.

The dashed broken lines throughout the drawing figures depict portions of the case for electronic communications device that form no part of the claimed design. The broken lines and regions bounded by broken lines form no part of the claimed design.
